UNITED STATES PATENT OFFICE.

JAMES M. WHITING, OF PROVIDENCE, RHODE ISLAND.

IMPROVEMENT IN MACHINES FOR THREADING WOOD-SCREWS.

Specification forming part of Letters Patent No. 35,406, dated May 27, 1862.

To all whom it may concern:

Be it known that I, JAMES M. WHITING, of Providence, in the county of Providence and State of Rhode Island, have invented a new and useful Improvement in Machines for Threading Wood-Screws; and I do hereby declare that the following is a full, clear, and exact description of the same, reference being had to the accompanying drawings, making part of this specification, in which—

Figure 1 is a plan of my improved machine. Fig. 2 is a side elevation of the same. Fig. 3 is an end elevation. Fig. 4 is an end elevation and section by line Z Z of Fig. 1 and 2. Figs. 5, 6, and 7 are details which are referred to in the course of the description.

Similar letters refer to like parts in all the figures.

The nature of my invention consists, first, in the employment of a face-plate having a series of studs fixed in its face at equal distances from each other and from its center for the purpose of carrying the tool or cutter from the head toward the point of the screw-blank to make the repeated cuts in forming the thread; second, in making the several studs of the series alternately larger and smaller in diameter with respect to each other, in the order in which they are placed, so that the cutter will be alternately advanced and delayed, and thereby made to cut first upon one side of the thread and then upon the other; third, in the employment of a series of adjustable cams projecting from the periphery of a rotating disk equal in number to the studs upon the face-plate, and acting, through the medium of a sliding former, to press the point of the tool or cutter against the blank to be threaded simultaneously with the action of the studs in carrying the tool forward to make the successive cuts in forming the thread; fourth, in the employment of a vertically-sliding carrier, which is made to ascend in the midst of a quantity of blanks contained in a dish or hopper whose bottom has a central inclination by repeated strokes or motions, and in so doing to lift one or more blanks from the mass and deposit the same between the prongs of a fork suspended by the head, from which they descend by an inclined railway to a horizontal position near the mouth of the nippers, to which they are fed by any well-known means.

To enable others skilled in the art to make

and use my invention, I will proceed to describe the construction and operation of the same by means of the accompanying drawings, in which—

A A is the frame or bed of the machine. B is a stand which forms one of two bearings in which the nippers revolve. These nippers are constructed, as shown, to grip and revolve the screw-blank while it is being threaded, and to this end they are operated by any well-known and effective mechanism which will open and close the same while revolving.

The tool or cutter d is formed as shown in Figs. 1 and 3, and firmly held in the tool-post D by means of the set-screw b between the cap e and a V-groove formed in the tool-post to receive it. This tool-post D is formed, as shown, with a sleeve, S, through which passes the round guide-rod E, on which it slides, and projecting arm f, extending downward and provided with a dog, n, of hardened steel, the purpose of which will presently appear.

F is the face-plate having a number of studs, h i i, &c., fixed in the face thereof, which in turn come in contact with the dog n as the face-plate revolves, which imparts a sliding movement to the tool-post D, in the direction indicated by the arrow, sufficiently rapid to produce the required number of threads to the inch upon the blank, which is revolved at a proportionate rate of speed to the distance moved by the tool-post in sliding upon the guide-rod.

The tool is returned preparatory to making a succeeding cut, when released from the studs, by means of the spiral spring g within the guide-rod, which bears against the step r, sliding in a slot formed lengthwise in the under side of the guide-rod, which is attached to the sleeve by the screw, as shown in Figs. 2, 3, and 4.

The guide-rod E turns in the stand B and a and has an arm, j, fixed upon it, the loose end being acted upon by the spiral spring g, as seen in Fig. 7, which swings the point of the tool away from the blank in the nippers, also the dog n from contact with the studs h and i, as shown in Fig. 4, and thus permits the tool to return after each cut is made, and also removes the tool from its proximity to the nippers while a threaded blank is being discharged therefrom and a fresh one inserted.

The tool is forced up to the blank suc-

sively to make the required number of cuts by means of the series of cams t , t , &c., attached by screws v , v , as shown, to the rotating disk G , Figs. 1 and 3. These cams are adjusted to give the required depth to the successive cuts and to deepen the successive cuts or cause the tool to cut successively deeper and deeper by means of the screws y , having a V or tapered point, as shown in Fig. 3. The cam-disk is supported in its position by the hollow standard H , inclosing the shaft by which it is revolved. Beneath said disk is placed a sliding piece, J , in which is secured the former k , against which the projecting top of the tool-post D' bears, as shown in Figs. 1 and 3. This former is formed with a cylindrical body at K , terminating in a rounded shoulder, and an enlargement at k' , the latter portion serving to press the tool in at the point of the blank to form the "gimlet-point." A pin, 2 , passes through the projections on the sliding piece J and through the former k , which is made fast thereto by a screw, as shown. Said pin is prevented from turning or sliding by the setscrew 3 , and, being thus arranged, if the former becomes worn after a time the screw 3 may be slackened, and by turning the former a new surface will be presented for the tool-post to act against.

In the sliding piece J is a fixed stud or post, 4 , having a flat surface upon one side, as shown in Fig. 1. The cams, in their turn revolving with the disk in the direction indicated by the arrows, come in contact with the post 4 , and in passing the same slide the sliding piece and former toward the blank, and by that means force the tool up to the blank at the proper time to cut the thread thereon.

It will be seen that there is the same number of cams upon the disk G as there are studs upon the face-plate F , and that one cam and one stud act simultaneously in their respective capacity in making each cut, and therefore of necessity they are moved together and act in combination.

It will be seen that the same movement of the cams t , t which carries the tool against the blank to make a cut also carries the dog n toward the face-plate to effect a connection with one of the series of studs h , i which reciprocates the tool, as seen in Fig. 3, and that the same movement of the cam which permits the withdrawal of the tool from the blank after each cut is made also permits the disconnection or unhooking of the dog n with the stud and permits the tool to return, preparatory to making another cut, as seen in Fig. 4, which, as a peculiar mode of operation, forms one feature of improvement in my machine.

It will also be seen that a space is left unoccupied upon the cam-disk between the first and last cam at 5 , which, while passing the post 4 , permits the tool to remain at rest and out of the way of the nippers while the threaded blank is being dropped therefrom and a fresh blank inserted.

It should be noticed that the several studs

are alternately larger (h , h , &c.) and smaller (i , i , &c.) in diameter, and from being thus varied from one medium diameter in each the former h , h advances the tool slightly and cuts upon one side of the thread only, and in the next succeeding movement produced by the latter i the tool is delayed and cuts upon the other side of the thread, as shown in Figs. 5 and 6, and the tool being made to cut deeper at each successive cut by the greater projection of the succeeding cams from the disk the thread upon the blank is finally cut to a sharp edge.

The blanks l are conveyed from the hopper M to the inclined railway T by means of the carrier N , sliding vertically in the standard of the hopper by motion transmitted from the revolving pitman K , whereby the carrier is made to slide upward three or more times during the threading of one blank. The bottom of the hopper inclines from the margin toward the center, which has the effect to keep the blanks placed therein around the carrier, in the top of which is formed a groove which selects a blank from the surrounding mass, as in ascending it passes through them. Above the carrier are two prongs, s , s , each united to the railway T in a hinge joint, as shown, and connected by the bow-spring x , which serves to return them to their proper position when by any means they become separated.

The several parts of the machine being constructed and arranged as above described, motion and power are communicated thereto by means of the main shaft P , which revolves the bevel-gears R , R , driving the sliding carrier N . The bevel-gears O and V , which drive the cam-disk G and face-plate F , and a third pair of gears which revolve the nippers and the several devices operate as follows: The carrier N at repeated ascending strokes lifts a blank, l , from the mass, forces it upward between the prongs S , which separate sufficiently to permit the head of the blank to pass when the carrier descends, leaving the blank suspended by its head between the prongs preparatory to raising another blank. From the prongs the blank slides down the railway to the nippers, where, by means of a punch actuated by a spring or any simple and effective device, the blank is presented to the nippers, which are made to seize it by the head while revolving. The first cam t' of the series in revolving next comes in contact with the post 4 of the sliding piece J , and in so doing presses the tool d up to the revolving blank, and the dog n of the arm f to one of the studs h' of the face-plate, whereby the tool is carried along the body of the blank and in at the point being governed by the shape of the former k , by which operation the first cut is made, when, by reason of the end of the cam t' passing the flattened side of the post 4 , the former retreats with the tool-post, removing the tool from the blank, and frees the dog n from the carrying-stud h' , as seen in Fig. 4, whereby the force of the spring y , which has been compressed, the tool-

post is returned preparatory to making a second cut, which follows in like manner to that just described by the action of the second cam of the series, and the next in the order of the studs *i*, which, being made smaller in diameter than the first, *h*, it retards the tool, so that instead of cutting in the same path with the preceding one it cuts only upon one side of the first path or cut, as seen in Figs. 5 and 6, which operation being repeated by the remaining cams and studs cutting first upon one side of the thread and then upon the other, as shown by Figs. 5 and 6, each succeeding cam pressing the tool deeper into the blank until the requisite number of cuts have been made to form a sharp thread upon the blank, after which it is dropped from the nippers, and another being supplied thereto from the railway the operation is continued, as before.

It has been specified above that during the threading of one blank the carrier *N* makes three or more ascending strokes. To explain the reason for which, it should be stated that in the event of the failure of one movement of the carrier to deposit a blank upon the prongs the two succeeding strokes are most certain to deposit a blank therein to replace that which is fed from the railway to the nippers.

Having thus described the construction and

operation of my improved machine, what I claim as my invention, and desire to secure by Letters Patent, is—

1. The face-plate *F*, and the series of studs *h i i*, in combination with the dog *n*, or its equivalent, upon the tool-post, arranged and operating substantially as described, for the purpose specified.

2. A series of studs which are alternately larger, *h h*, and smaller, *i i*, in diameter in the order in which they are arranged, substantially as described, for the purpose specified.

3. The combination and arrangement of the cams *t t*, &c., the studs *h i*, &c., and the springs *g* and *g*, for the purpose of effecting a connection and a disconnection at the proper time between the threading-tool holder and the device which reciprocates the same, substantially as described.

4. The sliding carrier *N*, arranged with the hopper *M*, in combination with the hinged prongs *S S* upon the railway, and operating substantially as described, for the purpose specified.
